Primary Examiner — T Chase Nelson*Assistant Examiner* — Sydney Margaret Parsley(74) *Attorney, Agent, or Firm* — McHale & Slavin, P.A.(57) **CLAIM**

The ornamental design for a shed, as shown and described.

DESCRIPTION

FIG. 1 is a top front right perspective view of the shed of the present invention;

FIG. 2 is a top rear left view thereof;

FIG. 3 is a front view thereof;

FIG. 4 is a rear view thereof;

FIG. 5 is a left side view thereof; and,

FIG. 6 is a right side view thereof.

The portions of the figures illustrated in broken lines form no part of the claimed design for the shed.

1 Claim, 6 Drawing Sheets(56)
